UNITED STATES PATENT OFFICE.

JOHN F. O'CONNOR, OF CHICAGO, ILLINOIS, ASSIGNOR TO WILLIAM H. MINER, OF CHICAGO, ILLINOIS.

FRICITION DRAFT-RIGGING.

1,136,035.

Specification of Letters Patent.

Patented Apr. 20, 1915.

Application filed December 26, 1911, Serial No. 667,593. Renewed August 12, 1914. Serial No. 856,490.

To all whom it may concern:

Be it known that I, JOHN F. O'CONNOR, a citizen of the United States, residing at Chicago, in the county of Cook and State 5 of Illinois, have invented a certain new and useful Improvement in Friction Draft-Rigging, of which the following is a full, clear, concise, and exact description, reference being had to the accompanying drawings, 10 forming a part of this specification.

My invention relates to improvements in friction draft rigging.

The object of my invention is to provide a friction draft rigging of simple, efficient and 15 strong construction, and one embodying great buffing and pulling resistance.

To this end my invention consists in a draw bar connected with a draft yoke, the latter having within it tandem arranged 20 friction cushioning devices, or a friction cushioning device arranged tandem with a spring cushioning device mounted in connection with the draft members of a railway car.

25 It further consists in the novel devices and the novel combination of parts and devices herein shown and described, and more particularly pointed out in the claims.

In the accompanying drawings which 30 form a part of this specification Figure 1 is a side elevation of a draft rigging with my friction element in vertical longitudinal section. Fig. 2 is a plan view of a draft rigging with my friction element shown in half 35 plan, and half partly in horizontal section. Fig. 3 is an enlarged cross section on line 3, 3 of Fig. 2. Fig. 4 is a longitudinal section of my friction cushioning element showing the position of parts when the device is com- 40 pressed solid. Fig. 5 is a front end perspective view of the spring cup or cap. Fig. 6 is an end perspective view of one of the friction blocks or wedges. Fig. 7 is an end perspective view of one of the friction blocks 45 showing inside of same. Fig. 8 is a side view of the friction blocks or wedges assembled. Fig. 9 illustrates a modification in side elevation partly in longitudinal section.

50 Referring to the drawings 9, 9 represents the center sills or draft members of the car frame to which the stop members 10 are secured, preferably by the rivets 11, 12, the draw bar. 13 the draft yoke, which is provided with the central upright bar or thumb- 55 ble 14, preferably integral with the yoke, the

said yoke being attached to the draw bar, preferably by means of the transverse key 15 passing through the slot 16 in the draw bar, and the slot 17 registering therewith in the yoke head 18, and also through the slots 19 60 in the draft members or center sills 9.

20 and 21 are the front and rear followers respectively, 22 and 23 the front and rear intermediate followers respectively, 24 the forward longitudinally movable friction 65 shell arranged between the followers 20 and 22, 25 the rear longitudinally movable friction shell arranged between the followers 23 and 21.

Each of the friction shells and contained 70 parts are identical, and I will therefore describe one of them. The friction shell is cylindrical in shape or circular in cross section, open at its forward end and closed at its rear end by the preferably integral 75 plate 26.

27 and 28 are two sets of oppositely arranged annular segmental wedging friction shoes, each set preferably comprising three segmental wedging shoes 29, all preferably 80 identical in shape or made from the same pattern, and each provided with an internal preferably integral seat or pin 30, which fits within one of the adjacent annularly arranged openings or perforations 31 in the 85 spring cup or cap 32. The said spring cup is cylindrical in form, and is provided at its rear end with an outwardly turned flange 33 against the forward face of which 34 the rear ends 35 of the rear set of annular seg- 90 mental friction shoes 28 abut. The friction shoes are in annular arrangement around the spring cup.

The numeral 36 designates a spring, the rear end of which is seated against the rear 95 inner end of the friction shell, and the forward end of which is seated against the inner face of the forward preferably integral end plate 37. The said spring is capable of being compressed within the spring cup on 100 full compression of the cushioning devices. The spring cup is provided at its forward end with an interiorly extended preferably integral hollow boss or lug 38 to receive within it the nut 39 suitably threaded on the 105 forward end of the connecting rod 40, which rod passes through the perforation 41 at the rear end of said boss and through the rear plate 26 of the friction shell, and is pro- 110 vided with the head 42 countersunk therein.

The longitudinal cylindric wall 43 of the boss 38 is sufficiently removed from the outer wall 44 of the spring cup to permit the reception of the spring 36 circumferentially between them and its seating around the boss 38.

The front ends 45 of the front set of annularly arranged friction shoes 27 are preferably more forwardly extended than the front end of the spring cup 32, and the follower adjacent bears against the front ends of said friction shoes. Each of the annular segmental friction shoes 29 has two inclined or wedging faces 46, 46^a. The annular segmental friction shoes of the front set interfit or internest circumferentially with the annular segmental friction shoes of the rear set.

The stop members 10 preferably have in addition to the front stop shoulders 47 and rear stop shoulders 48 and intermediate stop shoulders 49 and 50, front limiting stop shoulders 51 and 52, and rear limiting stop shoulders 53 and 54 for the followers to abut against. The tie plate 55 is secured to the draft members 9 by bolts 56. The boss 38 in the spring cup and the connecting rod 40 serve to hold the parts in assembled position, and also provide means for maintaining the spring under an initial compression, and also for automatically taking up the wear of the friction shoes.

The front and rear friction elements 57 and 58 respectively, each consisting of a friction shell and contained friction parts hereinbefore described, are placed within the draft yoke 13, the front friction element being between the followers 20 and 22 and within the forward lateral opening 59 of the said yoke, and the rear friction element 58 being between the followers 23 and 21 and within the rear lateral opening 60 of the draft yoke, the said openings being in tandem arrangement.

In the modification one of the lateral open-

ings of the yoke, preferably the rear one, is provided with a spring cushioning mechanism 61, and the other lateral opening is provided with my friction elements.

1 claim:—

1. In a railway draft rigging the combination of a draw bar, stop members, followers and yoke, of a friction shell, friction shoes, a spring cup and spring within the shell, the said spring being seated at one end within the spring cup and at the other end against the friction shell, and capable of being compressed within the spring cup on full compression of the cushioning devices.

2. In a railway draft rigging the combination with a draw bar, stop members, followers and yoke, of a friction shell, friction shoes, spring cup and spring within the shell, the said friction shoes being provided on their inner faces with a pin or teat, and the spring cup being provided with annularly arranged perforations for the reception of said pins.

3. In a draft gear, a shell, two sets of oppositely arranged friction shoes, a spring cup and spring within the shell, the said friction shoes being annularly arranged around the said spring cup.

4. In a draft gear, a shell, a spring cup, springs and two sets of oppositely arranged friction shoes within the shell, the said shoes being arranged around said spring cup, the said spring cup being provided at one end with an outwardly turned flange adapted to engage one set of friction shoes.

5. In a draft gear, a shell, friction shoes, a spring cup and a spring within the shell, the friction shoes being oppositely arranged about the spring cup, the said shoes being provided with means connecting them to the spring cup.

JOHN F. O'CONNOR.
